RECORD CARD ALIGNING DEVICE FOR STATISTICAL MACHINES

Filed Dec. 9, 1942

FIG. 1.

UNITED STATES PATENT OFFICE

2,328,612

RECORD CARD ALIGNING DEVICE FOR
STATISTICAL MACHINES

Eugen Buhler, Binghamton, N. Y., and David W. Rubidge, Chatham, N. J., assignors to International Business Machines Corporation, New York, N. Y., a corporation of New York

Application December 9, 1942, Serial No. 468,360

1 Claim. (Cl. 164—111)

This invention relates to machines in which record cards are fed from a supply hopper to instrumentalities which record data on the cards or derive data from the cards. Such cards are provided with columns of data receiving positions, which columns are spaced apart so that, as the cards are fed in the direction of the columns, the instrumentalities which are similarly spaced will cooperate with their respective columns.

The record cards are made of paper stock which is subject to atmospheric conditions so that where excessive moisture is present, an expansion of the card occurs with the result that the space between the extreme card columns is greater than when the cards are relatively drier and the column spacing does not conform exactly to the spacing of the instrumentalities with which the columns are to cooperate in their passage through the machine.

It is the object of the present invention to provide an aligning device which acts upon the cards prior to their cooperation with the recording or sensing instrumentalities, to centralize the card with respect thereto so that any undue expansion or contraction will be equally divided on both sides of the center of the card thus minimizing any misalignment of the end columns with their respective instrumentalities. The amount of misalignment usually occurring is well within allowable tolerances, but it is desirable that such be reduced as much as possible.

Other objects of the invention will be pointed out in the following description and claim and illustrated in the accompanying drawing, which disclose, by way of example, the principle of the invention and the best mode, which has been contemplated, of applying that principle.

In the drawing:

Fig. 1 is a fragmentary section through a punching machine showing the manner in which the aligning device is incorporated therein.

Fig. 2 is a view of the aligning device looking from the left of Fig. 1.

Figs. 3 and 4 are diagrams showing the principles of the aligning action.

The punching machine employed for purposes of illustration is similar to that shown in Patent No. 2,224,761 granted December 10, 1940 to A. H. Dickinson et al. and its operation will therefore be but briefly explained.

It comprises a record card magazine or supply hopper M from which the cards are fed singly by the card feeding means comprising in part the card picker 47 and 48 and actuating arm 46 with

5 operating cams 42 and 43 therefor, to feed rollers 80 and 81 to the usual card stacker, not shown. Interposed between rollers 80 and 81 is shown one type of card recording means, for example, the punch plungers 65 and control magnets 66 therefor.

The punch plungers 65, arranged in a row (Fig. 2) with one for each of the usual columns of the card, are located at a greater distance from the 10 card magazine than in the patent referred to in order to provide the necessary space to accommodate the aligning device.

The magnets 66 upon energization select associated plungers 65 so that during the operation 15 of the operating bar 67, the bar depresses or operates all the selected plungers and thereby effects perforation of the record card. It is well known that an individual plunger 65 and controlling magnet 66 are provided for each card 20 column and that all the selected plungers are depressed for all columns simultaneously, and that various positions along the several columns may be perforated.

More detailed explanation of the card feeding 25 and punching mechanism may be found in the patent referred to and also in reissue Patent No. 21,133 dated June 27, 1939.

Shaft 34 corresponds to the similarly identified shaft in Patent No. 2,224,761 and makes one 30 revolution for each card fed from the magazine M. This shaft carries a gear 10 which through an idler 11 drives a gear 12 on a shaft 13. The gear 12 meshes with suitable gears for driving the rollers 80 and the ratio is such that for each 35 revolution of shaft 13 a new card 14 is in position between the central pair of rollers 80 as shown in Fig. 1. When each card is in such position, the aligning operation is effected through the mechanism now to be described.

A frame 15 pivoted at 16 on a bracket 17 carries a plate 18 at its upper end which projects above the plane of card 14 and extends in the direction of the path of movement of the card. At the opposite side of the card is an equal lengthened frame 15a pivoted at 16a to a bracket 17a and having a plate 18a at its upper extremity. The pivots 16 and 16a lie in a horizontal plane parallel to the plane of travel of the card 14, so that the distance from pivot 16 to the point where plate 18 engages the card edge is exactly the same as the distance from pivot 16a to the point where plate 18a engages the opposite card edge.

At a point 19 of frame 15 there is pivoted one 55 end of a link 20 whose other end is pivoted at

21 to a depending arm of frame 15a. The distance between points 16 and 19 is the same as the distance between points 16a and 21 and the angle formed by a line through points 16 and 19 with a line through point 16, and the point at which 18 engages card 14 is the same as the angle formed by a line through points 16a and 21 with the extension of a line through point 16a and the point at which 18a engages card 14, so that, within a small radius, any rocking of frame 15 about its pivot 16 will be accompanied by rocking of the frame 15a to the same extent in the opposite direction.

A spring 22 attached to link 20 tends to urge frame 15a counterclockwise and frame 15 clockwise. The frame 15 carries a roller 23 in cooperative relationship with a face cam 24 mounted on shaft 13. During the greater part of the rotation of the cam its high cam portion holds roller 23 toward the left as viewed in Fig. 2 i. e. it holds frame 15 in a position as diagrammatically represented in Fig. 3 and through link 20 the frame 15a is also rocked as shown. Thus the upper end plates 18 and 18a are held away from the card edges.

When the card is in the position of Fig. 1, roller 23 drops into a low part of cam 24 whereupon spring 22 is free to rock the frames 15 and 15a to bring plates 18 and 18a against the edges of the card 14. The tension of spring 22 is divided equally between the two frames so that they engage the card with equal force and if at the time the card is slightly to the left or right as viewed in Fig. 2 it will be brought to a central position and momentarily guided therein as it passes to the last pair of feed rollers 30. The central pair of feed rollers 30, which engage the card at this time and advance it do not grip the card sufficiently to interfere with any sidewise motion imparted to it by the plate 18 or 18a. Fig. 4 shows in the same diagrammatic manner as Fig. 3 the position of the parts when the card is centralized.

From an inspection of the diagrams (Figs. 3

and 4) it will be noted that whether card 14 is slightly longer or shorter than the one in position in Fig. 4, the frames 15, 15a will nevertheless effect a centralization thereof with respect to the row of plungers 65.

While there have been shown and described and pointed out the fundamental novel features of the invention as applied to a single modification, it will be understood that various omissions 10 and substitutions and changes in the form and details of the device illustrated and in its operation may be made by those skilled in the art without departing from the spirit of the invention. It is the intention therefore to be limited 15 only as indicated by the scope of the following claim.

What is claimed is:

In a machine of the class described having a record card hopper, a row of elements with which the cards are to cooperate, and means for feeding the cards singly and in succession from the hopper to said row of elements, said means including pairs of feed rollers intermediate the hopper and row of elements, the combination with means for centralizing each card separately with respect to said row of elements while the card is passing through the feed rollers, comprising a pair of pivoted levers, one spaced from each edge of the card and parallel to the direction of movement of the card, the levers being fixedly pivoted in a plane parallel to the plane of travel of the card and equal in length, a link directly connecting the levers on opposite sides of their pivots whereby movement of either will be accompanied by equal and opposite movement of the other, a roller carried by one of the levers, a cam directly cooperating with said roller, a single spring acting upon the levers and link to rock the levers directly against the edges of the card 30 to centralize it, said cam being configured to release the roller to enable said spring to act at the same time for each card fed.
